UNITED STATES PATENT OFFICE.

NIKITAS LAPPAS, OF PEABODY, MASSACHUSETTS.

LOCK.

Application filed March 22, 1926. Serial No. 96,578.

The invention relates to improvements in locks and more particularly to keepers therefor, and the present application discloses a keeper which is primarily intended for use 5 in connection with permutation locking means, such as that shown by my U. S. Patent No. 1,571,125 of January 26, 1926. In the patented construction, the locking means included a plurality of coaxially mounted 10 locking members having laterally projecting arms, all of which could pass through an opening in a keeper plate, when said arms were alined by manipulation of a pair of rotatable members. It is the primary object 15 of the present invention however to provide a rotatable guard plate mounted at the inner side of the keeper plate and provided with means whereby it may be rotated, said guard plate being itself formed with an 20 opening which must be alined with the opening of said keeper plate, before the arms of the locking members can pass outwardly to permit release of the lock.

Another object of the invention is to provide 25 exceptionally simple and inexpensive, yet efficient means for mounting and rotating the guard plate.

With the foregoing in view, the invention resides in the novel subject matter hereinafter described and claimed, the description being supplemented by the accompanying drawing.

Figure 1 is a plan view of a lock embodying my improvements.

Figure 2 is a longitudinal sectional view as indicated by line 2-2 of Figure 1.

Figure 3 is a horizontal section as indicated by line 3-3 of Figure 2.

Figure 4 is a transverse sectional view on line 4-4 of Figure 3.

Figure 5 is a top plan view of the guard plate.

In the drawings above briefly described, A and B designate two members to be locked together. Secured to the member A by suitable fasteners 6 and 7, is a keeper 8, said keeper comprising a plate 9 having a laterally projecting annular flange 10 which bears against said member A. This plate is formed with an opening which preferably comprises a centrally disposed body portion 11 and a laterally extending portion 12.

The numeral 13 designates an outer plate which is suitably hinged at 14 to the member B, said plate preferably having a flange 15 which extends around the keeper 8. A

permutation locking mechanism 16 is mounted on the plate 13 and includes an assembly of locking members 17 having laterally projecting arms 18 which may be turned by the control members 19 and 20, so that all of them are in alinement or out of alinement, as the case may be, and when said arms are alined with each other as shown in Figure 2, being at that time alined with the lateral portion 12 of the keeper opening, they may pass through this opening, if it is not otherwise obstructed, so as to permit outward swinging of the plate 13 and consequent disconnection of the members A and B. When the arms 18 are out of alinement with the portion 12 of the opening, however and preferably out of alinement with each other, the plate 13 will of course be locked to the keeper 8, so that the members A and B are securely locked to each other.

The parts so far briefly described, are disclosed in my U. S. patent, above referred to, and no claim is being made for them except in connection with the improvements now to be described.

Rotatably positioned at the inner side of the keeper plate 9, is a guard plate 21 having an opening which preferably comprises a main portion 22 and a laterally extending portion 23, these portions being adapted for registration with the opening portions 11-12 of said keeper plate 9, when the guard plate is turned to the proper position. In fact, the portion 22 of the guard plate opening is always in registration with the portion 11 of the keeper plate opening, but when the device is locked, the portion 23 of said guard plate opening is out of registration with the portion 12 of said keeper plate opening. Thus, even though some unauthorized person should succeed in learning the necessary combination to aline the arms 18 with the portion 12 of the keeper plate opening, said arms could not at that time pass outwardly to release the lock, as they would then be obstructed by the guard plate 21. Hence, in order to open the lock, it is necessary to also know the proper position at which to set the guard plate, so as to aline the portions 12 and 23 of the openings, as seen in Figure 2. Means are of course provided whereby this guard plate may be rotated from the exterior of the lock. Preferably this plate is provided with a laterally projecting continuous flange 24 which engages the inner side of the flange 10 and is

provided with gear teeth 25. These teeth mesh with a pinion 26 whose shaft 27 rotatably passes through an opening in the flange 10 and has its inner end supported by an appropriate bearing 28. The outer end of this shaft 27 projects from the flange 10 and is received in a notch 29 in the flange 15 of the plate 13, the outer extremity of said shaft being equipped with a knob or the like 30 by means of which it may be rotated.

At a point diametrically opposite the pinion 26, I provide a roller 31 to engage the edge of the flange 24, so that this roller and the pinion 26, hold the plate 21 in engagement with the keeper plate 9, insuring smooth rotation of said plate 21. Preferably, the roller 31 is provided with gear teeth to engage the teeth 25 of the flange 24. Any desired means may be employed for 20 rotatably supporting this roller but I prefer to make use of a short shaft 32 having its outer end mounted in an opening in the flange 10, while its inner end is supported by an appropriate bearing bracket 33, secured to the inner side of said flange.

The peripheral portion of the guard plate 21, is provided with a plurality of numbers or other suitable indicating characters (see Figures 1 and 5) and these characters 30 are visible one at a time, through a view opening 34 in the two plates 9 and 13. The legitimate operator of the lock knows exactly what character must appear in the opening 34, in order for the portion 23 of the guard plate opening to be in alinement with the portion 12 of the keeper plate opening, and hence by turning the knob 30 until that character appears, he may readily release the lock. Obviously, the arms 18 40 may be alined and properly positioned by manipulation of the control members 19 and 20, either before or after the guard plate 1 is set at released position.

Excellent results have been obtained from 45 the details disclosed and they are preferably followed. However, within the scope of the invention as claimed, variations may of course be made.

I claim:

50 1. In a lock, a keeper plate having an opening, an outer plate engageable with the outer side of said keeper plate, permutation locking means mounted on said outer plate and including a locking member movable 55 through the opening of the keeper plate, a guard plate at the inner side of said keeper

plate movable either into obstructing or non-obstructing relation with the opening thereof and exposed means whereby said guard plate may be rotated.

60 2. In a lock, a keeper plate having an opening through which to insert a locking member, said keeper plate having a laterally projecting continuous flange, a guard plate at the inner side of said keeper plate having an opening which is adapted to be moved either into or out of alinement with the keeper plate opening to form an additional locking means, said guard plate being of circular outline and having its peripheral portion in engagement with and surrounded by said flange to be guided in its rotary movement thereby, and means for supporting said guard plate and rotating it.

70 3. In a lock, a keeper plate having an opening through which a locking member may pass, a said keeper plate having a continuous laterally projecting flange, a guard plate at the inner side of said keeper plate having an opening adapted to be moved into or out of registration with the keeper plate opening, said guard plate having a laterally projecting continuous flange which engages the inner side of the first named flange and is formed with gear teeth, rotatably mounted members carried by the first named flange and engaging the flange of said guard plate to rotatably support the latter, one of said rotatably mounted members having gear teeth meshing with the teeth of said guard plate flange, and exposed means connected with the toothed member for rotating it to thereby rotate said guard plate.

75 4. In a lock, a keeper plate having an opening, an outer plate engageable with the outer side of said keeper plate, permutation locking means mounted on said outer plate and including a locking member movable through the opening of the keeper plate, a guard plate at the inner side of said keeper plate movable either into obstructing or non-obstructing relation with the opening thereof, exposed means whereby said guard plate may be rotated, and circumferentially 80 spaced indicators on said guard plate, said keeper plate and said outer plate having a view opening through which said indicator may be seen.

85 In testimony whereof I have hereunto af- 110 fixed my signature.

NIKITAS LAPPAS.
